UNITED STATES PATENT OFFICE

DAVID H. COLLIER, OF CARBON, INDIANA

CLOTHESPIN

Application filed April 18, 1932. Serial No. 605,934.

This invention relates to clothespins of the two-arm forked variety, the objects of which are to provide a moulded resilient fastener of the two-arm forked variety; to provide a cleft fastener with the arms resiliently abutting each other; and to provide a weather-proof fastener which is durable in construction and simple and inexpensive to manufacture.

10 An illustrative embodiment of this invention is shown in the accompanying drawing in which:

Figure 1 is a side view of the clothespin in closed position with the clothesline in cross section.

Fig. 2 is a view similar to Fig. 1, showing the clothespin partially placed to a clothesline.

Fig. 3 is a view similar to Figs. 1 and 2, 20 showing the clothespin in locked position on a clothesline.

Fig. 4 is a sectional view taken on the line 4—4 of Fig. 3.

Fig. 5 is a perspective view of the clothespin and line.

Fig. 6 is a perspective view of a pair of clothespins showing them holding a garment on a clothesline.

Referring more in detail to the drawing, 30 a fastener or clothespin 1, preferably made of reclaimed rubber or the like, is cleft to form two arms 2 and 3, and is provided with an aperture 4 terminating at the end of the cleft. The arms 2 and 3 are provided at 35 their tips with mutually flared inner faces 7 forming a guide to contact with the wire clothesline 5.

In operation one end of the article 8 to be hung is placed on a clothesline and the 40 clothespin is placed in the position shown in Fig. 1 and pressed downwardly. The arms will then spread outwardly as shown in Fig. 2 and by further downward pressure the clothesline will finally be forced into perforatory aperture 4 as shown in Fig. 3.

Since the material forming the fastener is 45 resilient the arms formed by the cleft are normally held in contact with each other and any article placed in the cleft will be held by the spring of the material. In case the

article is placed over a clothesline and straddled by the moulded clothespin, it will be firmly held on the line. To release the article the tips of the arms are forced away from each other and the clothespin lifted 55 upwardly. The clothespin may then be replaced on the line and kept there for future use.

The clothespin may be easily cleaned if it becomes soiled, but the two inner faces of 60 the cleft will not become soiled under ordinary conditions as they abut against each other at all times.

Although but one specific embodiment of 65 this invention is herein shown and described, it is to be understood that details of the construction shown may be altered or omitted without departing from the spirit of the invention as defined by the following claims.

I claim:

1. As an article of manufacture, a cleft moulded rubber fastener having substantially parallel resilient clamp arms yieldingly abutting each other.

2. As an article of manufacture, a cleft moulded rubber fastener having substantially parallel resilient clamp arms yieldingly abutting each other, said cleft terminating in a perforatory aperture.

Signed at Carbon, in the county of Clay 80 and State of Indiana this 14th day of April, 1932.

DAVID H. COLLIER.
